UNITED STATES PATENT OFFICE.

JOSEPH GERBER, OF FREMONT CENTRE, MICHIGAN.

BOILER-FURNACE.

SPECIFICATION forming part of Letters Patent No. 252,656, dated January 24, 1882.

Application filed September 7, 1881. (No model.)

To all whom it may concern:

Be it known that I, JOSEPH GERBER, of Fremont Centre, in the county of Newaygo and State of Michigan, have invented an Improvement in Boiler-Furnaces, of which the following is a specification.

The nature of this invention relates to certain new and useful improvements in the construction of boiler-furnaces of that class designed for consuming spent tan, sawdust, and other refuse; and the invention consists in the peculiar construction and various combinations of the parts, all as more fully hereinafter set forth.

15 Figure 1 is a sectional perspective. Fig. 2 is a vertical cross-section through the arch and grate. Fig. 3 is a central vertical longitudinal section of Fig. 1.

In the accompanying drawings, which form 20 a part of this specification, AA represent steam-boilers, which are set in the usual manner. In front of these boilers I place my furnace, which is set in the walls B, access to the grate being had through the doors a a, the rear portion of 25 the furnace resting upon the bridge-wall C.

D represents the grate of my improved furnace, and may be of any desired construction adapted for burning fine fuel, such as spent tan, sawdust, &c. Over this grate I place 30 the arch E, which is constructed preferably of boiler-iron, said arch being double and water and steam tight.

F is a pipe through which water is fed into the arch, and G H are pipes running from the 35 arch to the boilers. Through the arch E are formed passages b, through which the fuel passes to the grate.

In practice the sawdust or other fine fuel is delivered upon the top of the arch E and falls 40 through the passages b upon the grate, where it is consumed, the heated products of combustion passing over the apron I beneath the boiler. By this construction I present all the boiler-

surface to the action of the heat, while I am enabled to burn matter as fuel that is ordinarily called "refuse," and that cannot be burned in ordinary furnaces. The arch being kept full of water, prevents the fuel from being ignited above it, while it throws off sufficient heat as to dry, or partially so, the fuel before it passes 45 to the grate. At the same time it performs the functions of a heater for heating the water before it passes to the boiler.

If desired, the arch E may be constructed of brick and built solid, with metal passages b 50 inserted. This construction will be preferable in some cases.

I am aware that it is not new to provide a furnace with a brick arch having openings to allow the feeding of fuel to a grate below, and 55 I am also aware that it is not new to place a water-arch in a furnace fire-box for the purpose of heating the feed-water, and therefore I do not broadly claim either of the constructions named, my invention being confined to 60 a water-arch supported midway in the furnace-walls and provided with feed-openings, whereby it is adapted to support and dry a quantity of fuel without burning the same before it 65 passes the feed-openings, and at the same time 70 to heat the feed-water.

What I claim as my invention is—

In a furnace, the water-arch E, supported midway between the grate and top of the furnace, and provided with openings b, leading to 75 the fire-box and connected to the boiler by suitable pipes, whereby it is adapted to support and dry refuse fuel without burning the same before it passes the feed-openings, and at the same time to heat the feed-water, substantially as shown and described.

JOSEPH GERBER.
